DOOR CLOSURE

Charles E. Klecan, Chicago, Ill., assignor to Philip R. Oftedal, Chicago, Ill., doing business under the style and firm name of Protex Weather-Strip Mfg. Co.

Application December 17, 1934, Serial No. 757,799

6 Claims. (Cl. 20—68)

My present invention relates to improvements in door closures, and has particular reference to door closures attached to the bottom or top of a swinging door or window.

5 The particular object of my invention is to improve the construction of door closures so as to reduce to the very minimum air space between the various parts of the mechanism, which has been an objection to door closures made and 10 marketed up to the present time, in which latter construction there is substantial air passing up and around the closure mechanism itself.

A further object of my present invention is to produce a construction in which leaf springs and 15 the like, which are relatively soon distorted and become inoperative, are dispensed with, and to produce a door closure in which none of the parts are required to be replaced.

This and other objects will be seen by an inspection of the drawings in the light of the specification.

In the drawings,

Fig. 1 represents an elevational view of a lower part of a door showing the door closure in closed operative position, parts of the said door closure being broken away;

Fig. 2 represents a longitudinal sectional view, with parts of the mechanism not shown;

Fig. 3 represents a cross section taken on the lines 3—3 of Fig. 2;

Fig. 4 is a cross sectional view taken on the lines 4—4 of Fig. 2;

Fig. 5 represents a cross sectional view on the lines 5—5 of Fig. 2;

Fig. 6 represents an enlarged view of the spring mechanism for returning the door closure in raised position;

Fig. 7 represents an enlarged view of the lever mechanism;

Fig. 8 represents a plan view of the actuating means taken on the line 8—8 of Fig. 2;

Fig. 9 represents a cross sectional view taken on the line 9—9 of Fig. 2;

Fig. 10 represents an end view of the lower part of the door and the improved door closure inserted within said door; and

Fig. 11 represents an end view of the lower part of the opposite edge of the door showing the hinged connection in cross section.

50 Similar reference characters are applied to the relative parts in the various figures shown, in which 1 represents the door casing, 2 the door itself, 3 the door-sill, 4 the adjustable rod, 5 the pivoted connection of said rod to the lever 6, 7 a cross bar which is welded or otherwise attached to a U-shaped casing 8, said cross bar being pivoted to the lever 6 at 9, 10 represents a roller pivoted at 11 to the lever 6, 12 is a metal plate on which said roller 10 makes contact when the lever is in the depressed condition, said plate be-

ing connected at 13 to the longitudinal extending felt retaining member 14, 15 represents the pin connection of the coil spring 16, which spring is connected through a hole 17 in the lever 18, said lever being journalled to the cross bar 8 by the pin 19, said lever 18 having a recess 20 for cooperation with the pin 21, which pin extends transversely across the felt retaining member 14, said felt retaining member 14 being braced by means of a series of pins 22, extending from side to side 10 of said felt retaining member 14, 23 represents a screw inserted in the door casing, 24 represents a metal plate through which the end of the rod 4 projects at 25 in alignment and for making contact with the screw 23, 26 represents the felt 15 or other compressible member, 27 represents a stem for reinforcing the connection between the threaded portion 28 of the rod 4, 29 the place at which said rod 4 enters the bifurcated arm 30, 31 represents the hinge of the door, 32 the end plate 20 for the door closure and 33 and 33^a the screws for attaching the plates to the door, 34 are the screws passing through the U-shaped casing 8 by which the door closure is attached to the door. Any other suitable means, however, may be used for permanently affixing the door closure to the door, such as inserting U-shaped lugs in the metal plates 24 and 32 to serve as a support for the vertical part of the U-shaped casing 8.

The rod 4, threaded as shown at 28, passes thru a threaded opening in the bifurcated arm 30, which arm makes the connection with the pin 5. The stem 27 serves to reinforce the connection between the threaded part 28 of the rod 4 and the bifurcated arm 30, and to lessen the tension on the threaded part 28 as pressure is applied to the end of the rod 25 upon opening and closing the door or window. Said end 25 is recessed to permit said rod to be turned so as to adjust the depth to which the lever 6 will extend upon the rod 4 being pressed inwardly. To carry out this adjustment most effectually the pin 5, when the lever 6 is in raised position, is located, as to vertical alinement, nearer the rod 4 than the pin 9 as clearly shown in the drawings.

45 Figures 1 and 2 show the structure in operative position, i. e. with the felt pressing against the lower part of the door-sill, the door being in closed position. When the door is closed the rod 4, pressing against the screw 23, is forced forward, 50 thus forcing the lever 6 downward against the plate 12 and thereby forcing the felt retaining member 14 downward and thus closing the aperture between the door and the door-sill. This lever 6 functions only for the purpose of thus depressing said felt retaining member. When the door is opened and the friction between the rod 24 and the screw 23 is removed the lever 13, being actuated by the spring 16, raises the said felt retaining member 14 to which it is pivotally con- 55 60

nected by means of the pin 21, said lever 18 thus functions only to return the felt retaining member in raised position. To reduce friction either one or two rollers on each side of said lever 6 may be used. Both of said levers 6 and 18 pivotally mounted on the cross bar 7 are situated within the contour of the felt retaining member 14, said felt retaining member thus being in longitudinal alinement and in close proximity with the sides 10 of the U-shaped casing 8.

There has been a serious objection to the structures heretofore marketed by reason of the fact that parts of the actuating mechanism have been attached to the outside of the felt retaining member, with the result that a considerable air space resulted between the U-shaped casing and the felt retaining member and thus the efficiency of the door closure has been seriously impaired. With my improved construction this air space is 20 eliminated and the retaining member is throughout the longitudinal length of the door closure in as close proximity to the U-shaped casing as is possible without friction between the two members.

25 Also in structures that are at the present time on the market, the structure necessitated the use of one or more leaf springs, which soon become inoperative by use and even by the initial insertion of the weather strip in the door, and frequently have to be replaced. With the construction herein shown this serious objection is 30 obviated.

As will be observed by an inspection of the drawings, particularly the slot 20, the felt retaining member is removable from the remaining portion of the device, which is an added advantage of applicant's structure; for when the felt retaining member must be replaced, it is not necessary to remove the entire casing from the door 40 but only the retaining member may be removed, a new felt may be inserted in the retaining member and thereupon the same may be reinserted in the casing.

45 While I have shown my improved invention inserted in a wooden door yet it is perfectly obvious that the invention may be enclosed in a metal housing and attached to either the front or back of a metal door without any change of structure or function.

50 Having thus described my invention what I claim is:

1. A door closure comprising a casing, a felt retaining member within said casing and adapted to engage a felt or other elastic substance, a rod 55 extending within the said retaining member, one end of said rod extending exteriorly of said member and adapted to coat with a door jamb, the other end of said rod pivotally mounted on a lever, said lever being adapted to press against the 60 said retaining member, a spring connected with a second lever having slidable engagement with said retaining member and adapted to return said retaining member in raised position when the contact of said first lever with said door jamb 65 is broken.

2. A door closure comprising a casing, a felt retaining member within said casing and adapted to engage a felt or other elastic substance, a rod extending within the said retaining member, one end of said rod extending through said member 70 and adapted to coat with a door jamb, the other end of said rod pivotally mounted on a lever, said

lever upon contacting said door jamb pressing the said retaining member downward, a coil spring connected with a second lever having slidable engagement with said retaining member and adapted to return said retaining member in raised position upon breaking the contact of said first mentioned lever with said door jamb. 5

3. A door closure comprising a casing, a felt retaining member within said casing and adapted to engage a felt or other elastic material, a rod 10 extending within said retaining member, one end of the same extending thru said member and adapted to coat with a door jamb, the other end pivotally mounted at or near the center of said retaining member on a single lever, said lever 15 upon contacting said door jamb pressing the said retaining member downward, a coil spring connected with a second lever having a slidable engagement with said retaining member and adapted to return said retaining member in raised position 20 on breaking the contact of said first mentioned lever with the said door jamb.

4. A door closure comprising a U-shaped casing, a felt retaining member within the casing, a metal plate connected with said retaining member, 25 a lever, a roller pivoted to said lever, a cross-bar within said casing to which is pivoted said lever, a rod extending exteriorly of said casing and adapted to press said lever downward when the rod is extended inwardly, a second lever journaled to said cross-bar having a recess therein 30 for cooperation with a pin attached to said retaining member, a coil spring, one end of which is attached to said second lever, and the other end of said coil spring attached to said casing. 35

5. A door closure comprising a U-shaped casing having a cross-bar therein securely attached thereto, a lever pivoted to said cross-bar, a rod having cooperative connection with said lever and tending to press said lever downward when the rod is extended inwardly, a felt retaining member, a metal plate affixed to said member, said metal plate having cooperative contact with said lever, a second lever having a recess therein, a pin journaled in said retaining member normally inserted in said recess, said pin being readily removable from said recess, said second lever journaled in said cross-bar, a coil spring attached to said lever at the opposite side from said recess, and the other end of said coil spring attached to 50 said casing.

6. A door closure comprising a U-shaped casing having a cross-bar therein securely attached thereto, a lever pivoted to said cross-bar, a rod having cooperative connection with said lever and tending to press said lever downward when the rod is extended inwardly, a felt retaining member, a metal plate affixed to said member, said metal plate having cooperative contact with said lever, a second lever having a recess therein, a pin journaled in said retaining member normally inserted in said recess, said pin being readily removable from said recess, said second lever journaled in said cross-bar, a coil spring attached to said lever at the opposite side from said recess, 60 and the other end of said coil spring attached to said casing, the vertical sides of said cross-bar, both of said levers, the said plate and the said spring all being inside the vertical contour of said retaining member. 65

CHARLES E. KLECAN.
